TUBULAR LOCK

Frederic K. Heyer, Stamford, Conn., assignor to
 The Yale & Towne Manufacturing Company,
 Stamford, Conn., a corporation of Connecticut

Application December 11, 1948, Serial No. 64,735

27 Claims. (Cl. 70—223)

1

This invention relates to a tubular lock, and more particularly, to the tubular lock described and claimed in my application for patent, Serial No. 698,936 filed September 24, 1946, which issued as Patent No. 2,538,683 on January 16, 1951.

In the said application I show a rollback casing adapted to be positioned in a transverse bore formed in a door and to be united with a latch-bolt casing inserted in a bore beginning at the edge of the door and running toward the bore into which the rollback casing is secured. The rollback casing shown in my application houses a rollback adapted to be actuated by a spindle that in turn is rotated by a pair of spindle operators, there being one spindle operator at each end of the rollback casing. Each spindle operator is adapted to be maintained in a central neutral position by a pair of control rings and is rotatable clockwise or counter-clockwise from the said neutral position by a knob secured thereto.

In my earlier application, I show a single solid spindle positioned in the rollback casing and operated by the two spindle operators so that the inside knob and the outside knob are rotatable together at all times. Thus, my earlier lock can be characterized as comprising a rollback casing having a pair of centrally positioned spindle operators capable of rotation independently of one another by knobs, with the two spindle operators being joined for operation together when a single solid spindle is assembled relatively thereto.

In my present application, I utilize substantially the same rollback casing as in my earlier application and the very same arrangement of spindle operators and spindle operator centering means. However, I use an entirely different spindle construction so that the knobs are rotatable relatively to one another. Similarly, I provide means for locking the outside spindle operator and its knob against rotation, means being provided to allow rotation of the outside spindle operator upon suitable actuation of key operated mechanism. The control means for effecting the locking of the outside spindle operator and the outside knob are mounted in the inside knob and are readily controlled as will be indicated presently.

In other words, I utilize substantially the same casing, rollback, and spindle operator construction as in my earlier lock, but by providing two spindles instead of one, together with different knobs, I obtain entirely different controls and entirely different operations. Thereby I make it possible to utilize the basic combination of my earlier application for yielding operations re-

2

quired for store doors, outside apartment house doors, and for other installations as will be readily appreciated by those skilled in the art.

As a further feature of my invention, I utilize a split spindle comprised of two parts, one called outside and one called inside, both spindle ports being normally positioned within the rollback contained in the rollback casing. It will be readily appreciated that if the outside part of the split spindle is moved outwardly of the rollback, it will no longer be effective to rotate the rollback. For so positioning the spindle, I utilize means mounted within the rollback casing and actuated by an extremely novel construction of the inside knob.

As a particular feature of the invention that is of considerable importance, the outside spindle is pushed into what may be considered the locked position thereof through the medium of yielding means. Thereafter, the outside spindle may be moved back through compression of the yielding means to render the outside spindle effective, but without disturbing the means that were first used to move the outside spindle into its locking position. Because of this construction, once the outside spindle is placed in locked position by the operation of the means in the inside knob, it can be moved into and out of locked position through other means without disturbing the setting of the means in the inside knob. Those skilled in the lock art will readily appreciate the extreme desirability of this functioning of my invention.

As a further more particular feature of the invention, the outside spindle when moved out of the rollback is adapted to be locked against rotation so that a double locking thereof is effected. In other words, the outside spindle is not only not in engagement with the rollback but is also held against rotation.

In the tubular locks of the prior art, there is frequently provided a push button on the inside knob for locking the outside knob, and in many locks the push button is depressed to lock the outside knob and then remains depressed until the inside knob is rotated or the latch-bolt is retracted, these operations releasing the button for outward movement. Where the lock is applied to an outside door, it is generally necessary to move the push button into locked position and then maintain it there until the push button is actually manually released rather than automatically released by the closing of the door or the turning of the inside knob. For this purpose there are provided means whereby the push button is first moved inwardly against the force of a

spring and then rotated into locked position. Thereafter, to release the push button, it is rotated first in a reverse direction and then allowed to spring outwardly. Such operation of the push button is extremely difficult, especially for women and children. In another type of lock of this class, locking is effected by a turn button carried by the inside knob. This type of button is also difficult to manipulate.

I have conceived a construction using a push button that may effect locking without turning thereof. Thus, my push button, when pushed inwardly, effects a locking of the mechanism, the push button then moving outwardly again to a predetermined position, while leaving the mechanism locked. Upon a second inward pushing of the push button, it releases the locking mechanism and moves outwardly once again. In other words, my invention comprises the locking first by a first push on the push button and the release thereafter of the locking mechanism by a second push on the push button.

I have thus outlined rather broadly the more important features of my invention in order that the detailed description thereof that follows may be better understood, and in order that my contribution to the art may be better appreciated. There are, of course, additional features of my invention that will be described hereinafter and which will form the subject of the claims appended hereto. Those skilled in the art will appreciate that the conception on which my disclosure is based may readily be utilized as a basis for the designing of other structures for carrying out the several purposes of my invention. It is important, therefore, that the claims be regarded as including such equivalent constructions as do not depart from the spirit and scope of my invention, in order to prevent the appropriation of my invention by those skilled in the art.

Referring now to the drawings, Fig. 1 is a vertical section through the rollback casing of my lock and the inside and outside operating knobs. Fig. 2 is a section taken along the same lines as Fig. 1, but showing the outside spindle and outside knob locked against rotation. Fig. 3 shows the parts carried by the inside knob in a different operating position. Fig. 4 is a view taken along lines 4-4 of Fig. 2. Fig. 5 is a section taken along lines 5-5 of Fig. 2. Fig. 6 is a section taken along lines 6-6 of Fig. 2. Fig. 7 is an exploded view of the parts of the inside knob push button and the mechanism actuated thereby. Fig. 8 shows an inside knob equipped with a key operated mechanism for locking and releasing the outside spindle. Fig. 9 shows two of the important parts utilized in the combination of Fig. 8. Fig. 10 is a perspective view of the outside spindle. Fig. 11 is an elevation of the inside knob while Fig. 12 is an elevation of the outside knob. Fig. 13 is a partial vertical section showing the latchbolt casing and its relation to the rollback casing. Fig. 14 shows the latchbolt casing assembled to the rollback casing with the two knobs and their roses in operating position.

Referring now more particularly to the drawings, and especially Figs. 11 to 14 inclusive, the latchbolt casing of my invention is designated by reference numeral 10 and has mounted therein a latchbolt 11 adapted to be retracted by a push piece 12 shown more particularly in Fig. 13. This push piece 12 is mounted for movement to the left in Fig. 3 upon rotation clockwise or counter-clockwise of the rollback 13 mounted within the rollback casing indicated generally by refer-

ence numeral 14. It will be noted that the rollback casing has threaded sleeve portions 15 on which are adapted for rotation parts for supporting the roses 16. The inside knob of my lock is designated by reference numeral 17 and is adapted to have mounted therein a push button 18, the outside knob being designated by reference numeral 19 and carrying a cylinder lock 20 best shown in Fig. 1 within which is mounted a key plug 22 best shown in Fig. 12.

The rollback casing 14 is formed of two halves, as is quite apparent through reference to Figs. 1, 2, and 14. Essentially, the rollback casing is exactly the same as that of my earlier application supra except that the two parts comprise a series of nesting lugs 23, each having an upstanding shoulder 24. By passing a wire 25 between the upstanding shoulders 24 of the lugs 23, the two casing halves are locked together and are prevented from separation. I have found this construction superior to that of my earlier casing construction wherein I use a series of matching lugs adapted to be locked together by a spring sleeve.

25 The latchbolt casing 10 has a pair of arms 26 adapted to enter the rollback casing 14 and to be locked thereto by means fully claimed and set forth in my earlier application supra. It is between these two arms 26 that the push piece 12 is positioned for actuation by the rollback 13, also as set forth in my earlier application. To understand the present invention it is only necessary to know that I use a rollback to retract a latchbolt, my invention residing here in the control of the spindles that rotate the rollback.

26 The outside spindle operator of my invention is designated by reference numeral 27 as best seen in Figs. 1 and 2, and is mounted for free rotation relatively to the rollback casing 14.

30 Part of the spindle operator 27 lies within one of the sleeve portions of the rollback casing 14, while part thereof is within a central rollback chamber of the rollback casing, a suitable retainer ring 28 being utilized for retaining the spindle operator 27 against movement outwardly of the rollback casing.

35 The inner spindle operator is designated by reference numeral 29 and is mounted within the rollback casing 14 in substantially the same manner as is the spindle operator 27. A pair of control rings 30, best shown in Figs. 1 and 2, coact with a spring 31 and a longitudinal rib 32 of the rollback casing 14 to maintain the spindle operator 27 in a predetermined rotated neutral position relatively to the rollback casing 14. Thus, the control rings function through the spring 31 to return the spindle operator 27 to the position illustrated in Fig. 1 whenever the spindle operator is rotated clockwise or counter-clockwise. Similarly, a pair of control rings 33 function to maintain the outer spindle operator 29 in a neutral rotated position relatively to the rollback casing 14. The construction of the control rings 30 and their manner of functioning is well set forth and claimed in my earlier application supra and is therefore not described in more detail here.

40 The rollback 13 is formed with a square bore 34 in which is adapted to be mounted the inner spindle 35 and the outer spindle 36, the spindles being square and therefore slidable relatively to the bore 34 in the rollback 13. The spindles are similarly slidable in square bores of the two spindle operators. The end of the inner spindle 35 is turned down slightly at 37 as probably best seen in Fig. 7, to cut down the corners thereof and

is formed with a pin portion 38 lying within a bore 39 of the spindle 36.

A slot 49 is formed on the upper surface of the inner spindle 35 as best seen in Figs. 1 and 7, and cooperating with this slot 49 is the lug 41 of a slide 42. Slide 42 is formed with a groove 43 within which lies a spring 44, the right hand end of which as seen in Fig. 1, bears against a surface of inner spindle operator 29, whereby to urge the slide 42 toward the left in Fig. 1. The slide is retained against movement completely outwardly of the spindle operator 29 through a scalp 45 applied to the end of the spindle operator 29 and having an inwardly extending shoulder coacting with the curved end 46 of the slide 42. Inner spindle 35 is formed also with a bore 47 within which is positioned a compression spring 48, the left end of which presses against an arm 49 depending downwardly from slide 42 and equipped with a spring guiding pin 49a. It is the function of spring 48 to maintain the inner spindle 35 in its position of Fig. 1 relatively to slide 42. It is the further function of the spring 48 to act as an intermediary between slide 42 and the spindle 35 whereby movement of the slide 42 to the right in Fig. 1 will move the spindle 35 to the right in Fig. 1 and to the position of Fig. 2. The spring 48 has a further function whereby to allow movement of the spindle 35 to the left from its position of Fig. 2 without moving slide 42, all as will be set forth hereinafter.

The inner spindle operator 29 carries a spring operated retaining plunger 50 normally positioned in alignment with a bore 51 of the left sleeve portion of the rollback casing 14, as seen in Figs. 1 and 2. The retaining plunger 50 is adapted to enter a retaining bore 52 in a part 53 of the inner knob 17 whereby when the knob is slipped over the spindle operator it will be retained against outward movement as fully shown in the drawings. Naturally, by the mere insertion of a tool into the bore 51, the retaining plunger 50 may be depressed and the knob 17 removed.

Knob 17 is fashioned of sheet metal as is fully shown in the drawings and is adapted to have secured thereto a cup 54 of sheet metal, best shown in Figs. 3 and 4. The knob 17 is furthermore formed so as to have a central opening 55 within which operates the push button 18 earlier referred to and probably best illustrated in Figs. 3 and 4 taken together with Fig. 7.

Push button 18 is formed of sheet metal adapted to be forced over the end of a peculiarly shaped plunger 56 best seen in Fig. 7. Plunger 56 is formed with a central longitudinal slot 57 within which moves an odd-shaped detent 58 best illustrated in Figs. 1 and 3 and resembling best an inverted U. One leg of the detent 58 is designated by reference numeral 59, and it moves relatively to a spring containing bore 60 of the plunger 56. A spring 61 lies within this bore 60 of the plunger 56 and acts to press the detent 58 into its position of Figs. 1 and 2. A spring 62 is positioned between the bottom of the cup-shaped member 54 and a surface of the plunger 56 whereby normally to urge the plunger 56 and the push button 18 into the position of Figs. 1 and 2. Slidably mounted about the plunger 56 is a sleeve-like push piece 63 best shown in Fig. 7. At the right hand end of the push piece 63 is a pin 64 adapted for coaction with the arm 49 of the slide 42 as is fully shown in the drawings. Push piece 63 is formed with a longitudinal slot 65 adapted for alignment with the slot 57 of the plunger 56. It is also formed with a transverse

slot 66 adapted for coaction with a dog 67 pivotally mounted at 68 within the cup 54 and urged by a spring 69 toward the slot 66. Push piece 63 is formed with an opening 70 adapted to expose a slot 71 in the plunger 56. Operating within the opening 70 and within the slot 71 is part of a dog 72 pivoted at 73 to the cup 54 and urged by a spring 74 toward the slot 71.

When the parts are positioned as in Fig. 1, the spring 62 holds the plunger 56 and the push button 18 in the position of Fig. 1, the outward movement of the plunger 56 being limited through coaction of the dog 72 with the shoulder 71a defining the right hand end of the slot 71 in plunger 56. At the same time, the dog 67 will press against the upper surface of the push piece 63 to the right of the slot 66 thereof. Pin 64 of the push piece will be against the depending arm 49 of the slide 42. Detent 58 will lie as seen in Fig. 1, being held by its spring 59a in the particular position illustrated.

Let us now see what happens when the push button 18 is pressed inwardly or to the right in Fig. 1. As the push button 18 moves to the right, it carries with it the detent 58 and the push piece 63, all moving against the force of the spring 62 and spring 44. Naturally, movement to the right will cause the pin end 64 of the push piece 63 to move the slide 42 into the position of Fig. 2, thereby acting through the spring 48 to effect movement to the right of the inner spindle 35 and the outer spindle 36. During this movement the cam surface 58a of the detent 58 will merely act to press the dog 67 upwardly against the force of its spring 69, after which the detent 58 will be positioned to the right of the dog 67. As soon as the slot 66 of the push piece 63 moves opposite and under the dog 67, that dog will ride into the slot 66 as shown in Figs. 2, 3 and 4 and the push piece 63 will thereafter be locked in the position of Fig. 1. However, push button 18 and the plunger 56 do return to the position of Figs. 1 and 2, and to explain this movement an intermediate position of the push button 18 and the plunger 56 is illustrated in Fig. 3.

During movement of the push button 18 and plunger 56 to the left from a position in which the right end of detent 58 is at the right of dog 67, the surface 58b of the detent 58 will ride against the dog 67 and will be held by the dog 67 against further movement to the left with the plunger 56. This will allow the downwardly tapered end surface 75 of the plunger 56 to move with the push button 18 away from detent 58 and cut from under the bottom of the right hand leg of the detent 58. This is possible because spring 69 is more powerful than spring 61. At this point the detent 58 will move downwardly to the position of Fig. 3 through the compression of spring 61, with dog 67 camming the detent 58 downwardly to allow detent 58 to move to the left of dog 67 and back to its normal relation to the plunger 56 and the push button 18 illustrated in Figs. 1 and 2. In other words, as the push button 18 moves to the left of Fig. 3 to the position of Fig. 2, it leaves the push piece 63 behind it securely locked by the dog 67, detent 58 being first cammed below the dog 67 and then pushed outwardly by its spring 61 into its normal position relatively to the push button 18.

In the position the parts have now reached, the slide 42 and the push piece 63 are held by the dog 67 so as to maintain the spindles 35 and 36 in the position illustrated in Fig. 2. Let us assume it now becomes desirable to allow movement

of the spindle 35 to the left from its position of Fig. 2 and back to its position of Fig. 1. This movement will be imparted to the spindle by the influence of means acting against the outer spindle 36, and also by the spring 44 operating between slide 42 and inner spindle operator 29. However, such movement of the spindles cannot be accomplished until push piece 63 is released from the dog 67. Such release is effected by a second inward movement of push button 18, this inward movement being considerably less, however, than was required to move the parts originally into the position of Fig. 2.

Thus, if push button 18 is moved to the right in Fig. 2, surface 58a of the detent 58, being held against downward movement as in Fig. 3 by a solid surface of the plunger 56, acts solidly against the dog 67 and moves it firmly against the force of its spring 69 so as to withdraw it from the slot 66. Immediately thereafter, the push piece 63 is moved to the left and back to its position of Fig. 1 relatively to push button 18. In other words, the same push button that effects a movement to the right of the spindles when first depressed, releases the spindle holding mechanism and allows a movement thereof to the left upon a second and sequential depression thereof. The extreme value of this part of my construction will be appreciated at once by those skilled in the art.

During all this movement of the several parts just described, dog 72 acts as a limiting member relatively to the push piece 63 and the plunger 56. The outer spindle 36 may be formed of a single piece as best illustrated in Fig. 10. Thus, it will have at its right end a cylindrical portion 78 having a cam surface projecting therefrom and designated by reference numeral 79. Standing from this cylindrical portion 78 is a guiding and locking member 80 formed with a slot 81 adapted for coaction with a rib 82 formed as an integral part of the right hand sleeve portion of the rollback casing 14. On the other hand, the outer spindle 36 may be formed of square stock for ready assembly, as best illustrated in Figs. 1 and 2, to a cylindrical member 78a having a cam portion 79a and a guiding and locking member 80a formed with a slot 81a. Actually, whether or not the parts are constructed as in Figs. 1 and 2 or as in Fig. 10 is immaterial to the operation of the invention.

When the outer spindle 36 is in its position of Fig. 1, the left end thereof is within the bore 34 of the rollback so that rotation of the spindle by the outside spindle operator 27 will effect rotation of the rollback. Moreover, the slot 81a of the guiding and locking member 80a is to the left of the rib 82 so that the spindle 36 is free to be rotated by the spindle operator 27 within which it slides. However, when the spindle 36 is moved to the position of Fig. 2 through actuation of the push button 18 as earlier described, the slot 81a of the guiding and locking member 80a will ride over the rib 82, thereby locking the outer spindle 36 against rotation. Outside spindle 36 is, in the position of the parts in Fig. 2, outside of the bore 34 of the rollback so as not to prevent the rotation of the rollback by and with the inner spindle 35. At this point, it will be well to indicate that through the cutting away of the inner spindle 35 at 37, a safety zone is created so that the inner spindle in the position of the parts in Fig. 2 may be free to rotate even though a part thereof is within the square bore of the now locked spindle operator 27.

The outer spindle operator 27 has pinned there-

to at 83 an outer knob 19 formed of sheet metal 84 shaped to contain therein a cylinder 20 equipped with the usual key plug 22 having an operating bar 85. It is the function of the bar 85 to rotate a cam 86 equipped with a cam surface 87 adapted for coaction with the cam surface 79a at the end of the cylindrical portion 78a that rotates with outer spindle 36. A spring 88 bears at its left end within a shallow bore 89 in cylindrical portion 78, or a bore 89a in the cylindrical part 78a of the modification of Fig. 1 or 2. In either case spring 88 urges the spindle 36 to the left in the position of the parts in Figs. 1 and 2, the right hand end of the spring 88 bearing against a surface of the cam 86 and being guided by a suitable guide pin 90 formed integrally with the cam 86. It is the function of the spring 88 to maintain the outer spindle 36 firmly against the inner spindle 35, whereby the outer spindle 36 will follow the inner spindle 35 to its extreme left position shown in Fig. 1 while resisting the movement of the two spindles to the right into the position of Fig. 2.

Let us say now that the spindle 36 has been moved into the position of Fig. 2 wherein it is locked against rotation and locks also the spindle operator 27. The outer knob is now, of course, held against rotation and entry through the door on which the lock is applied is impossible. Of course, anyone can operate the inside knob and the inside spindle 35 to retract the latchbolt so that egress is possible. With the parts thus positioned in Fig. 2, should a key be inserted in the key plug 22 and the plug rotated, its bar 85 will rotate cam 86, bringing the cam surface 87 against the cam surface 79a. It will now be possible to move the cylindrical member 78a to the left, bringing the slot 81a away from the rib 82, whereupon the parts will be positioned as shown in Fig. 1. At this point, the outer spindle 36 has been released for rotation and may rotate with the knob 19 and spindle operator 27 to retract the latchbolt through rollback 13.

During this movement of the spindle 36 to the left, the spindle 35 was also moved to the left, compressing the spring 48 and bringing shoulder 41a, defining the left end of the slot 40 of spindle 35, away from the lug 41 of the slide 42. This movement of the inner spindle 35 does not in any way affect the positioning of the slide 42 and the push button 18 and its associated mechanism, including push piece 63 that holds slide 42 in the position of Fig. 2. Therefore, once the latchbolt is retracted and the knob 19 is thereafter allowed to move with the cylinder and key plug 22 back to the position of Fig. 2, the spindle 36 must also move to the right to its position of Fig. 2. In other words, the parts will once again be locked, and should re-entry be desired, the key plug 22 must once again be rotated.

The operation of my invention will now be quite apparent. Thus, it will be seen that with the parts in the initial position of Fig. 1, a full depression of push button 18 will effect a locking of the outer spindle 36 and the outer knob 19 through a movement of the spindle 36 to the right. This movement is effected through the intermediary of the relatively strong spring 43 operating against the relatively weak spring 88 that holds the outer spindle 36 firmly against the inner spindle 35. With the parts locked as in Fig. 2, they may be released by a slight inward movement of the push button 18 sufficient to bring surface 58a of the detent 58 against the dog 67. If the parts remain locked as in Fig. 2,

operation from the outside is possible through actuation of the key plug 22. Thus, rotation of the key plug 22 will through the cam surface 87 operate a cam surface 79a, and effect a movement of the spindle 36 to the left from its position of Fig. 1 sufficient to unlock the spindle and bring it into the square bore of the rollback 13. Such movement does not disturb the push button 18 and its associated mechanism, but effects only the compression of the spring 48 so that a return of the cylinder 20 and key plug 22 with the knob 19 back to the position of Fig. 2 will effect the return of the parts into the locking position through the operation of the spring 48. Therefore, once the locking mechanism is locked from the inside, it can be released permanently by a slight depression of the push button 18. It can be released temporarily at any time from the outside by rotation of the key plug 22.

Under some circumstances, the key plug 22 may be arranged to operate through a particular distance so that it will lock the outer spindle 36 in release position even though the push piece 63 is locked by dog 67 in its position of Fig. 2. Under such circumstances, the latchbolt may be retracted by both the inside and outside knobs regardless of the positioning of the push button and its control mechanism.

Referring now to Figs. 8, 9, and 10, I show a modification of the construction of the inside knob. Thus, the inside knob 17a of Fig. 8 is substantially a duplicate of the knob 17 of Fig. 1, except that it carries, instead of the push button and its associated mechanism, a cylinder lock 91 equipped with a key plug 92 that rotates an end bar 93 adapted to rotate a cam 94, best shown in Fig. 9. Cam 94 is mounted within the inside spindle operator 29 and is held in position by the scalp 45, this being the same scalp that is utilized in the first modification described to hold slide 42 in position.

Cam 94 is formed with a cam surface 95 adapted for coaction with the curved surface 46 at the left end of slide 42, this being the same curved surface that in my first modification fits against the end of the scalp 46. In the modification of Fig. 8, rotation of the key plug 92 will cause the cam surface 95 of cam 94 to coact with the curved surface 46 of slide 42 to move the said slide 42 in exactly the same manner as the said slide is actuated by push piece 63 and its pin 64 in my first modification. In other words, rotation of the key plug 92 will effect the locking of the outer spindle in the same manner as this locking is accomplished by push button 18 in the first modification. The particular construction described is intended for use in installations where unauthorized locking of the outside knob or unauthorized releasing of the outside knob must be prevented. Thus, no one can lock or unlock the outside knob of the modification of Fig. 8 except by a key cut to fit the key plug 92. In all other respects, the operation of the parts of Figs. 8, 9, and 10 is exactly the same as that of my earlier modification and need not further be described here.

The operation and functioning of my invention should now be clear to those skilled in the art.

I now claim:

1. In a lock of the class described, a rollback, a pair of spindles, means mounting said spindles for sliding movement transversely relatively to said rollback, both said spindles being normally positioned with a part thereof in operating rela-

tion to said rollback, an operator, means mounting said operator for movement relatively to said rollback, spring means extending between said operator and said spindles whereby movement of said operator effects movement of said spindles transversely of said rollback through the intermediary of said spring means, and means for moving said spindles relatively to said operator against the pressure of said spring means.

10 2. In a lock of the class described, a rollback having a bore, a pair of spindles slidable in said bore transversely relatively to said rollback and each adapted to rotate said rollback, both said spindles being normally positioned in said bore with a part thereof in operating relation to said rollback, an operator, means mounting said operator for movement relatively to said rollback, and spring means extending between said operator and said spindles whereby movement of said operator effects movement of said spindles through the intermediary of said spring means to move one of said spindles out of said rollback bore.

3. In a lock of the class described, a rollback having a bore, a pair of spindles slidable in said bore transversely relatively to said rollback and each adapted to rotate said rollback, both said spindles being normally positioned in said bore with a part thereof in operating relation to said rollback, an operator, means mounting said operator for movement relatively to said rollback, and spring means extending between said operator and said spindles whereby movement of said operator effects movement of said spindles through the intermediary of said spring means to move one of said spindles out of said rollback bore, an outside knob for rotating said one of said spindles to rotate said rollback, and means carried by said knob for moving said spindle back into said rollback bore against the pressure of said spring means.

4. In a lock of the class described, a housing, a rollback in said housing having a bore, an inside and an outside spindle rotatably mounted on said housing with both spindles having portions in said rollback bore in operating relation to said rollback and slideable relatively thereto, an operator, means mounting said operator on said housing for movement relatively thereto, and spring means extending between said operator and said spindles whereby movement of said operator effects movement of said spindles through the intermediary of said spring means to move said outside spindle out of the rollback bore.

5. In a lock of the class described, a housing, a rollback in said housing, an inside and an outside spindle rotatably mounted on said housing with both spindles in operating relation to said rollback and slideable relatively thereto, an operator, means mounting said operator on said housing for movement relatively thereto, and spring means extending between said operator and said spindles whereby movement of said operator effects movement of said spindles through the intermediary of said spring means.

6. In a lock of the class described, a rollback having a bore, a pair of spindles slidable in said bore transversely relatively to said rollback and each adapted to rotate said rollback, both said spindles being normally positioned in said bore with a part thereof in operating relation to said rollback, an operator, means mounting said operator for movement relatively to said rollback, and spring means extending between said operator

and spindles whereby movement of said operator effects movement of said spindles through the intermediary of said spring means to move one of said spindles out of said rollback bore, and means for moving said spindle back into said rollback bore against the pressure of said spring means.

7. In a lock of the class described, a housing, a rollback in said housing having a bore, an inside and an outside spindle rotatably mounted on said housing with both spindles having portions in said rollback bore in operating rotation to said rollback and slideable relatively thereto, an operator, means mounting said operator on said housing for movement relatively thereto, spring means extending between said operator and said spindle whereby movement of said operator effects movement of said spindles through the intermediary of said spring means to move said outside spindle out of the rollback bore, and key operated means carried by said housing for moving said spindle back into said rollback bore against the pressure of said spring means.

8. In a lock of the class described, a housing, a rollback in said housing having a bore, an inside and an outside spindle rotatably mounted on said housing with both spindles having portions in said rollback bore in operating relation to said rollback and slideable relatively thereto, an operator, means mounting said operator on said housing for movement relatively thereto, and spring means extending between said operator and said spindle whereby movement of said operator effects movement of said spindles through the intermediary of said spring means to move said outside spindle out of the rollback bore, inside and outside knobs for rotating said inside and outside spindles, means carried by said inside knob for effecting movement of said operator to move said outside spindle out of said rollback bore, and means carried by said outside knob for moving said spindle back into said rollback bore against the pressure of said spring means.

9. In a lock of the class described, a housing, a rollback in said housing having a bore, an inside and an outside spindle rotatably mounted on said housing with both spindles having portions in said rollback bore in operating relation to said rollback and slideable relatively thereto, an operator, means mounting said operator on said housing for movement relatively thereto, and spring means extending between said operator and said spindle whereby movement of said operator effects movement of said spindles through the intermediary of said spring means to move said outside spindle out of the rollback bore, an outside knob for rotating said outside spindle to actuate said rollback when said spindle is within said rollback bore, and key operated means carried by said knob for moving said spindle back into said rollback bore against the pressure of said spring means.

10. In a lock of the class described, a rollback, a pair of spindles slideable transversely relatively to said rollback and each adapted to rotate said rollback, both said spindles being normally positioned with a part thereof in operating relation to said rollback, a push piece for pushing said spindles relatively to said rollback whereby to move the outer of said spindles into locked position, a knob for rotating the inner of said spindles, a dog for locking said push piece in depressed position to maintain said outer spindle locked, a push button in said knob for pushing said push piece into its depressed position upon a first push on said push button, and means where-

by said push button moves said dog to release said push piece for outward movement out of depressed position when said push button is pushed inwardly a second time.

11. In a lock of the class described, a rollback having a bore, a pair of spindles slideable in said bore transversely relatively to said rollback and each adapted to rotate said rollback, both said spindles being normally positioned in said bore with a part thereof in operating relation to said rollback, a push piece, means mounting said push piece for movement relatively to said rollback with a part of said push piece adapted to move said spindles to position one of said spindles out of said rollback bore, a knob, a dog for locking said push piece in depressed position to maintain said one spindle locked, a push button in said knob for pushing said push piece into its depressed position upon a first push on said push button, and means whereby said push button moves said dog to release said push piece for outward movement out of depressed position when said push button is pushed inwardly a second time.

12. In a lock of the class described, a rollback, a pair of spindles slideable transversely relatively to said rollback and each adapted to rotate said rollback, both said spindles being normally positioned with a part thereof in operating relation to said rollback, a push piece for pushing said spindles relatively to said rollback whereby to move the outer of said spindles into locked position, a dog for locking said push piece in depressed position to maintain said outer spindle locked, a push button for pushing said push piece into its depressed position upon a first push on said push button, and means whereby said push button moves said dog to release said push piece for outward movement out of depressed position when said push button is pushed inwardly a second time.

13. In a lock of the class described, a rollback having a bore, a pair of spindles slideable in said bore transversely relatively to said rollback and each adapted to rotate said rollback, both said spindles being normally positioned in said bore with a part thereof in operating relation to said rollback, a push piece, means mounting said push piece for movement relatively to said rollback with a part of said push piece adapted to move said spindles to position one of said spindles out of said rollback bore, a dog for locking said push piece in depressed position to maintain said one spindle locked, a push button for pushing said push piece into its depressed position upon a first push on said push button, and means whereby said push button moves said dog to release said push piece for outward movement out of depressed position when said push button is pushed inwardly a second time.

14. In a lock of the class described, a rollback having a bore, a pair of spindles slideable in said bore transversely relatively to said rollback and each adapted to rotate said rollback, both said spindles being normally positioned in said bore with a part thereof in operating relation to said rollback, an operator, means mounting said operator for inward movement relatively to said rollback, spring means extending between said operator and said spindles whereby said inward movement of said operator effects movement of said spindles through the intermediary of said spring means to move one of said spindles out of said rollback bore, means locking said operator in its inward position once it is depressed into said posi-

tion, an outside knob for rotating said one of said spindles to rotate said rollback, and means carried by said knob for moving said spindle back into said rollback bore against the pressure of said spring means while said operator remains locked in its inward position.

15. In a lock of the class described, a rollback having a bore, a pair of spindles slidable in said bore transversely relatively to said rollback and each adapted to rotate said rollback, both said spindles being normally positioned in said bore with a part thereof in operating relation to said rollback, an operator, means mounting said operator for inward sliding movement relatively to said rollback, means extending between said operator and said spindles whereby movement of said operator effects movement of said spindles through the intermediary of said means to move one of said spindles out of said rollback bore, means locking said operator in its inward position once it is depressed into said position, an outside knob for rotating said one of said spindles to rotate said rollback, and means carried by said knob for moving said spindle back into said rollback bore while said operator remains locked in its inward position.

16. In a lock of the class described, a housing, a rollback in said housing, an inside and an outside spindle rotatably mounted on said housing with both spindles in operating relation to said rollback and slidable relatively thereto, an operator, means mounting said operator on said housing for inward and outward movement relatively thereto, spring means extending between said operator and said spindles whereby inward movement of said operator effects movement of said spindles through the intermediary of said spring means, means for locking said operator in its inward position, an inside knob having a push button, means whereby a first push on said push button moves said operator inwardly whereupon it is locked, and means whereby a second push on said push button releases said operator from said locking means for outward movement.

17. In a lock of the class described, a housing, a rollback in said housing, an inside and an outside spindle rotatably mounted on said housing with both spindles in operating relation to said rollback and slidable relatively thereto, an operator, means mounting said operator on said housing for inward and outward movement relatively thereto, means extending between said operator and said spindles whereby inward movement of said operator effects movement of said spindles through the intermediary of said means to move said outside spindle out of operative relation to said rollback, an outside knob for rotating said outside spindle to actuate said rollback, and key operated means carried by said knob for moving said spindle back into operative relation to said rollback while said operator remains in its inward position, said means extending between said operator and said spindles being constructed to permit said spindle movement.

18. In a lock of the class described, a housing, a rollback in said housing, an inside and an outside spindle rotatably mounted on said housing with both spindles in operating relation to said rollback and slidable relatively thereto, an operator, means mounting said operator on said housing for movement relatively thereto, spring means extending between said operator and said spindles whereby movement of said operator effects movement of said spindles through the intermediary of said spring means to move said

outside spindle out of operating relation to said rollback, inside and outside knobs for rotating said inside and outside spindles, a key plug carried by said inside knob and rotatable for effecting movement of said actuator to move said outside spindle out of operating relation to said rollback, and means carried by said outside knob for moving said spindle back into operative relation to said rollback against the pressure of said spring means.

19. In a lock of the class described, a push piece, a spring pressing said push piece to an unlocking position, locking means movable by said push piece when depressed against the force of

15 of said spring, a dog for locking said push piece in a depressed locking position, a push button for pushing said push piece into its depressed position upon a first push on said push button whereupon it is locked by said dog, and means whereby 20 said push button moves said dog to release said push piece for outward movement out of depressed position when said push button is pushed inwardly a second time.

20. In a lock of the class described, a push 25 piece, a spring pressing said push piece to an unlocking position, locking means movable by said push piece when depressed against the force of said spring, a dog for locking said push piece in a depressed locking position, a push button for pushing said push piece into its depressed position upon a first push on said push button whereupon said dog locks said push piece in said depressed locking position, a spring for pressing said push button outwardly away from said push 30 piece to its original position, and a detent member movable with said push button for moving said dog out of locking position upon a second push on said push button whereby to release said push piece for movement by its spring to its unlocking position.

21. In a lock of the class described, a push piece, a spring pressing said push piece to an unlocking position, a dog for locking said push piece in a depressed locking position, a push button for pushing said push piece into its depressed position upon a first push on said push button, a detent carried by said push button and yieldingly held in a predetermined position relatively thereto, said detent moving said dog to a release position when said push button is pushed inwardly a predetermined distance, said detent thereafter releasing said dog to lock said push piece upon further inward pushing of said push button and push piece, a spring for pressing said pushbutton outwardly away from said push piece to its original position, said detent during said outward movement functionally by-passing said dog to leave it in its position locking said push piece, and the inward movement of said push 55 button and detent thereafter a limited distance effecting the release movement of said dog to release said push piece for movement by its spring toward its unlocking position.

22. In a lock of the class described, a push 60 piece, a dog for locking said push piece in depressed position, a push button for pushing said push piece into its depressed position upon a first push on said push button, and means whereby said push button moves said dog to release said push piece for outward movement out of depressed position when said push button is pushed inwardly a second time.

23. In a lock of the class described, a push piece, a dog for locking said push piece in depressed position, a push button, a spring pressing

said push button outwardly relatively to said push piece, the depression of said push button moving said push piece into a depressed position whereupon it is locked by said dog in said depressed position, a detent movable with said push button, means mounting said detent for positive movement with said push button inwardly in the direction of said push piece, and for yielding movement in a reverse direction, said detent having a cam surface for moving said dog out of locking position as it moves past said dog during the inward stroke of said push button and detent, said detent yieldingly moving relatively to said dog during the return stroke of said push button to leave said dog in locking position.

24. In a lock of the class described, a knob, a push piece carried by said knob, a dog for locking said push piece in depressed position relatively to said knob, a push button mounted on said knob, a spring pressing said push button outwardly of said knob and relatively to said push piece, the depression of said push button moving said push piece into a depressed position whereupon it is locked by said dog in said depressed position, a detent movable with said push button, means mounting said detent for positive movement with said push button inwardly of said knob, and for yielding movement in a reverse direction, said detent having a cam surface for moving said dog out of locking position as it moves past said dog during the inward stroke of said push button and detent, said detent yieldingly moving relatively to said dog during the return stroke of said push button to leave said dog in locking position.

25. In a lock of the class described, a locking member, a knob, a push piece carried by said knob, a dog for locking said push piece in depressed position relatively to said knob, a push button for pushing said push piece into its depressed position upon a first push on said push button, and means whereby said push button moves said dog to release said push piece for outward movement out of depressed position when said push button is pushed inwardly a second time.

26. In a lock of the class described, a locking member, a knob, a push piece carried by said knob, a dog for locking said push piece in depressed position relatively to said knob, a push button mounted on said knob, a spring pressing

said push button outwardly of said knob and relatively to said push piece, limit means for limiting the movement of said push button outwardly of said knob, the depression of said push button moving said push piece into depressed position whereupon it is locked by said dog in depressed position, a release part movable with said push button outwardly of said knob thereafter and relatively to said push piece and dog, said release part moving into position, once past and outside relatively to said dog, whereby upon depression of said push button thereafter it moves said dog to release said push piece for movement outwardly of said knob.

27. In a lock of the class described, a locking member, a knob, a push piece carried by said knob, a dog for locking said push piece in depressed position relatively to said knob, a push button mounted on said knob, a spring pressing said push button outwardly of said knob and relatively to said push piece, limit means for limiting the movement of said push button outwardly of said knob, the depression of said push button moving said push piece into depressed position whereupon it is locked by said dog in depressed position, a release part carried by said push button and lying in a position to extend inwardly of said dog when said push button is depressed, said release part being movable with said push button outwardly relatively to said knob thereafter and relatively to said push piece and dog, said release part moving into position, once past and outside relatively to said dog, whereby upon depression of said push button thereafter it moves said dog to release said push piece for movement outwardly of said knob.

FREDERIC K. HEYER.
